UNITED STATES PATENT OFFICE

156,001

DESIGN FOR A DOLL HOUSE

Mabel I. Haynes, Rockford, Ill.

Application February 14, 1948, Serial No. 144,509

Term of patent 3½ years

(Cl. D34—15)

To all whom it may concern:

Be it known that I, Mabel I. Haynes, a citizen of the United States, residing at Rockford, in the county of Winnebago and State of Illinois, have invented a new, original, and ornamental Design for a Doll House, of which the following is a specification, reference being had to the accompanying drawings, forming part thereof.

In the drawings:

Figure 1 is an end elevation of a doll house, embodying my new design, the opposite end being a mirror image of Figure 1;

Fig. 2 is a backside elevational view thereof;

Fig. 3 is a front side elevational view thereof, and

Fig. 4 is a perspective view thereof.

I claim:

The ornamental design for a doll house, substantially as shown and described.

MABEL I. HAYNES.
